UNITED STATES PATENT OFFICE

2,430,594

MAGAZINE STOVE WITH GAS COMBUSTION CHAMBER

Paul Wingert, Montpelier, Ohio

Application July 16, 1942, Serial No. 451,097

1 Claim. (Cl. 126—73)

1

This invention relates to improvements in stoves, furnaces and the like, and is a continuation-in-part of my co-pending application, Serial No. 377,511, filed February 5, 1941, now Patent No. 2,345,519, for Draft tube for stoves and furnaces.

The main objects of my invention are to provide an improved internal construction for stoves and furnaces; to provide a new and novel liner for stoves and furnaces having a sealed magazine; to provide a corrugated liner for stoves and furnaces of the sealed magazine type; to provide a pair of corrugated liners for a sealed magazine of a stove or furnace, which liners are arranged to abut against the inner front and rear walls of the stove shell respectively so that the grooves on the side of the corrugated members facing the said walls of the stove shell form closed vertically extending passageways; the upper end of the corrugated members being capped while the lower ends of the so-formed passageways are arranged to communicate with the ash pit chamber; to provide in such arrangement of parts perforations, slots or the like in the corrugated members adjacent their upper ends whereby any volatile gases accumulating in the upper end of the magazine may be drawn into the aforesaid passageways through said perforations and be discharged into the ash pit chamber and below the grate line; to provide in a device of this character, an improved safety means for the sealed magazine to prevent the creation of gas pressures therein and to obviate danger of explosion; to provide a combustion device of this character wherein the velocity of travel of the products of combustion is relatively slow and completely under control at all times; and to provide a new and novel stove or furnace which is relatively simple in construction and extremely efficient in operation.

A specific embodiment of this invention is shown in the accompanying drawing in which:

Figure 1 is a horizontal cross-sectional view taken on the line 1—1 of Figure 2.

Figure 2 is a vertical cross-sectional view taken on the line 2—2 of Figure 1.

Figure 3 is a vertical cross-sectional view taken on the line 3—3 of Figure 2.

Figure 4 is a perspective view of the fuel feed door.

Figure 5 is a sectional view taken on the line 5—5 of Fig. 3.

Referring in detail to the drawings, the stove to which this invention relates is of the sealed magazine type, and the magazine herein disclosed is defined by a pair of cast iron or steel corrugated front and back walls 1 and 2, and a pair of side walls 3 and 4, constructed of fire brick, the

2

lower ends of which are spaced away from grates 5 a predetermined distance and held in such position by suitable brackets 6 and 7. The upper end of the corrugated wall 1 is capped or sealed by any suitable means such as a cover plate 8. The upper end of the corrugated wall 2 abuts against the lower portion wall 9 of the upper chamber 10 and is thereby sealed at this end. The lower ends of the corrugated walls 1 and 2 bear against the grate plate 11. The grate plate 11 is provided with spaced marginal openings 12 aligned with the lower ends of the grooves in the corrugated members. The upper end of the corrugated walls 1 and 2 are provided with perforations or slots 14 the purpose of which will be hereinafter described.

The sealed magazine is enclosed in a suitable housing or shell 15 preformed to any desired size and shape and constructed of any suitable material such as heavy steel. The stove shown is also provided with a fuel feed door 16 having a handle 17; an ash pit chamber 18 having the usual ash pit door 19 hingedly connected to the door frame 20. The ash pit door 19 is also provided with suitable regulator means, not shown, for controlling the amount of primary draft air entering the ash pit 18 through the door 19 as will be understood by those skilled in the art. The upper chamber 10 communicates with the stack 30 through suitable piping 21.

As shown in Figs. 3 and 5 the upper chamber 10 is separated from the magazine by the wall portion 9. This wall portion 9 lies on top of the walls 3 and 4, and is spaced above the same by means of downwardly inclined portions 9b which terminate at their forward ends in vertically extending walls 9a which extend upwardly to the top of the casing and forwardly into engagement with the casing 15 so as to cooperate with the door 16 and the sealing ring R to seal the magazine.

The fuel feed door 16 is also provided with a downwardly extending flange 22 which acts as a safety by-pass damper door and it is arranged to completely cover the opening 23 in the side wall 45 of the upper chamber so that the feed door 16 is swung upwardly around pivot 24 to open the same, the damper door 22 swings forwardly and upwardly away from the opening 23 (see Fig. 3), thereby uncovering the same to permit any volatile gases accumulating in the upper end of the sealed chamber to escape to the upper chamber 10 and out the stack. This substantially removes any danger of the gases escaping into the room when the fuel feed door 16 is opened.

The grates 5 are pivotally secured to the grate frame 11 in the usual manner and are operable through manual movement of the grate bar 25.

The grate frame 11 is held in position in any suitable manner such as by brackets 26.

It will be apparent from the drawings, especially Fig. 1, that the corrugated walls 1 and 2 abut against the inner front and rear walls of the shell 15 thereby forming closed passageways 13. The passageways 13 are arranged to communicate with the ash pit chamber 18 below the grate line. The purpose of these passageways will be herein-after described. The walls 3 and 4 are spaced away from the shell 15 (see Figs. 1 and 2) and thereby form the radiators 27—28 respectively through which the products of combustion pass from the combustion chamber to the upper chamber 10.

Metallic baffle plates 29 and 30 are placed diagonally one in each of the lower ends of the radiators 27 and 28 respectively, see Fig. 2. The lower edges of each of the plates 29 and 30 bear against the grate frame 11 while the upper edges thereof bear against the inner wall of the shell 15.

The angle at which the baffle plates 29 and 30 are set is predetermined, as the area of the opening, i. e., the opening between the bottom edges of walls 3 and 4 and the faces of baffle plates 29 and 30 respectively, is definitely affected by the relationship of the angular position of the baffle plates and the bottom edges of walls 3 and 4. It will be apparent that the greater the angle, the larger the opening and vice versa.

After the fire has been started in the magazine, the magazine may be completely filled with fuel since combustion takes place at the grate line and the products of combustion are drawn off at the grate line and pass into the radiators 27 and 28. The products of combustion passing through the radiators 27—28 respectively co-mingle in the upper chamber 10 and thence pass out to the stack.

Any volatile gas which accumulates above the fuel bed will be drawn into the passageways 13, through the perforations 14 and be directed downwardly to the ash pit and be emitted below the grate line, where it admixes with the draft air entering the ash pit through the ash pit door 19. The combined fresh air and volatile gases then pass upwardly through the grates 5, to convert the gas into a flame.

As the magazine of the stove is completely closed on top and has no direct connection with the stack, while the feed door 16 is closed, and because of the draft effect of the stack in the radiators 27 and 28, the gases driven off from the heated fuel in the magazine, excepting that gas which passes through the perforations 14, are drawn downwardly from above and within the fuel bed along the inner wall surfaces of the fire-brick walls 3 and 4 and the walls 1 and 2 and through the hot coke on the grate where they admix with the combined fresh air and volatile gases coming from the ash pit chamber 18, to convert the gases into a flame.

The result is that the firebrick walls 3 and 4 become very hot and the heat thereof "cuts" the coal in the magazine and causes it to move downwardly very slowly and easily; thereby preventing the coal from "freezing up" and caking or arching. Since there is but a slight fuel bed resistance an extremely low draft is all that is necessary in a normal operation. This results in a slow lazy flame travel through the radiators, allowing ample time for the transfer of heat to the room, and thereby giving lower than average stack temperatures.

It will also be apparent that the products of

combustion in the radiators must pass through restricted openings between the lower ends of the walls 3 and 4 and the faces of baffle plates 29 and 30 to reach the upper chamber 10; hence providing more time for the products of combustion to remain in the radiators and allowing ample opportunity for them to give off their heat. The purpose of providing the upper chamber 10 is to afford a more uniform distribution of the products of combustion as they pass from the radiators 27 and 28, thereby obviating cool areas in the upper rear portions of the radiators.

It will be understood that corrugated firebrick may be substituted in place of the cast iron or steel corrugated side walls 1 and 2, thereby cutting down the weight of the stove as a whole. Such firebrick would, of course, be provided with perforations similar to those indicated by the numerals 14 in the cast iron or steel plates disclosed in the drawings.

In order to prevent primary draft air or the volatile gases emitted into the ash pit chamber 18 from passageways 13 from entering the radiators 27 and 28 because of leaks around the upper edges of the baffle plates 29 and 30 where they bear against the inner walls of the shell 15, I have secured partition plates 31 and 32 in the ash pit chamber. The plates are secured therein in any suitable manner, such as by bolts 33, and thereby restrict the area of the ash pit chamber and effectively accomplish the results sought. As clearly shown in Fig. 2, the plates 31 and 32 are set in the ash pit chamber 18 in such a manner that they substantially form a continuation of the baffle plates 29 and 30 respectively and seal off the area directly below the radiators 27 and 28 so that this area becomes a dead air space.

The stove as a whole is also provided with the usual legs 34 to space it from the floor upon which the stove is to be set.

Although but one specific embodiment of this invention is herein shown and described, it is to be understood that some of the details set forth may be altered or omitted without departing from the spirit of this invention as defined by the following claim.

I claim:

A stove of the class described wherein combustion takes place at the grate line and the products of combustion are withdrawn at the grate line comprising a shell having a top wall, a sealed magazine located within said shell, grates located below said magazine, an ash pit chamber provided with a primary draft damper, a fuel feed door in said shell and communicating with said sealed magazine, a chamber located in the upper end of said shell and defined by side, top and bottom walls, and a pair of radiators each defined by a vertically extending firebrick lining and the inner face of a portion of said shell, said sealed magazine being defined by a portion of the top wall of said shell, the bottom wall of said chamber, the inner faces of said firebrick lining 50 55 60 65 70 75 80 85 90 95 forming a pair of side walls, and front and back walls having spaced vertical corrugations parallelly disposed against the respective inner walls of said shell the lower portions of said side walls of said magazine being spaced away from said grates to provide communication between said magazine and said radiators, said corrugated walls and shell forming a series of independently arranged enclosed passageways which terminate in said ash pit chamber, each of said passageways being closed at their upper ends and said corrugated

gated walls having perforations therein located adjacent the upper end thereof whereby volatile gases accumulating in the upper end of said magazine may be drawn through the perforations into said passageways and directed into said ash pit chamber, admixed with primary air in said ash pit chamber and the admixture returned to said magazine.
